UNITED STATES PATENT OFFICE.

HARVEY H. WELSH, JR., OF WILMERDING, PENNSYLVANIA, ASSIGNOR TO THE WESTINGHOUSE AIR BRAKE COMPANY, OF PITTSBURG, PENNSYLVANIA, A CORPORATION OF PENNSYLVANIA.

OPENING DIE.

No. 853,289.

Specification of Letters Patent.

Patented May 14, 1907.

Application filed May 18, 1901. Serial No. 60,837.

To all whom it may concern:

Be it known that I, HARVEY H. WELSH, Jr., a citizen of the United States, residing at Wilmerding, county of Allegheny, State of Pennsylvania, have invented or discovered a certain new and useful Improvement in 5 Opening Dies, of which improvement the following is a specification.

My invention relates to dies for cutting 10 threads upon bolts, screw plugs, caps, and the like, and has for its object to provide a die which may be quickly opened and closed.

My invention consists in an improved construction of die having movable slides for 15 carrying the cutting dies and means whereby the slides may be moved toward or from each other in order to open or close the die.

In the accompanying drawings, which 20 illustrate an embodiment of my invention, Figure 1 is a vertical section of my improved die taken on the line $z-z$ of Fig. 2; Fig. 2 is a horizontal section taken on the line $x-x$ of Fig. 1; Fig. 3 is a vertical central section taken at right angles to Fig. 1; Fig. 4 is a 25 plan view of the die body with the slides removed; Fig. 5 is a side elevation of my improved die complete; Fig. 6 is a plan view of the two slides carrying the cutting dies, the slot covers being removed; Fig. 7 is a plan 30 view of the cam ring for operating the levers; Fig. 8 is a section of a portion of one of the slides, taken on the line $y-y$ of Fig. 6, and Fig. 9 is a side view of one of the cutting dies showing the groove therein.

The die-body 1 is made of cast iron and is 35 substantially cylindrical in form, having two segmental cut-away portions forming two plane faces on opposite sides of the body. The die-body 1 is mounted in position in a 40 lathe or other machine where it is to be operated, by means of a shank 2, which is secured to the bottom of the body portion. The upper face of the die-body is provided with two parallel gibs or guides 3 on which the 45 slides 4 are adapted to be moved. In the rounded sides of the die body are vertical slots 5 which extend the entire length of the body portion and in these slots the levers 6 are pivoted by means of bolts 8. The upper 50 ends of the levers 6 extend into slots 9 in the slides 4 while the lower ends of these levers are adapted to engage with the surface of a cam ring or collar 7, which is mounted to

turn upon the shank 2. Through the center of the die body there is an opening 14 in 55 which is located a spiral spring 10. The two slides 4 have studs 12 secured therein, the heads of which extend down through slots 13 into the opening 14. At the ends of the spring 10 are thimbles 11 which bear 60 against the studs 12, and in this way the two slides 4 are forced in opposite directions against the upper ends of the levers 6. When the cam ring is turned so that the two recesses 15 in the face of the cam ring are in 65 line with the lower ends of the levers 6 the spring will force the two slides 4 apart and the lower ends of the levers will drop into the recesses 15. Then by a further turn of the cam ring the lower ends of the levers will 70 be forced out by the cam surfaces 16 and the spring 10 will be compressed.

A semi-cylindrical portion of each slide 4 is cut away to form a central circular opening 17. The slides are also provided with 75 radial slots 18, in which are located the cutting-dies 19. These cutting-dies are adjustable toward and from the center by means of screws 20, which are tapped into the outer ends of the radial slots. After being 80 adjusted to the proper position the cutting-dies 19 are securely clamped by the conical wedges 21 and screws 22. The conical wedges are located in holes 23 in the upper face of the slides 4, close to the radial slots 85 18 and the cutting-dies 19 are provided with longitudinal grooves 25 into which the conical wedges project, as shown in Fig. 8. The groove has an inclined surface, which corresponds with the conical surface of the wedge 90 so that, as the wedge is screwed down the cutting-die is forced against the other side of the radial slot and securely held.

Thin plates or covers 24 are provided for 95 the top of the openings or slots 9 in the slides to keep out the dirt and other matter which might interfere with the operation of the levers.

The cutting-dies being properly adjusted by screws 20 and securely clamped in position by the conical wedges 21, the handle of the cam ring 7 may be turned so that the lower ends of the levers 6 drop into the slots or recesses 15, and the spring 10 forces the two slides 4 apart, thus opening the die. The 100 work may then be placed in position in the 105

lathe or other machine and the die closed by giving the cam ring another quarter turn, which moves the lower ends of the levers outward and forces the two slides, carrying the 5 cutting-dies, inward to their operating position. It will thus be seen that the operation is very simple and the die may be quickly and easily opened or closed by a mere quarter turn of the handle of the cam ring.

10 My invention is not limited to the exact construction shown, as certain changes of form and arrangement of parts may be made without departing therefrom.

15 What I claim and desire to secure by Letters Patent is:—

1. In an opening-die, the combination with a die-body having levers pivoted thereto, of movable slides engaged by the levers and mounted to reciprocate on said die-body,

a spring located in an opening in the die- 20 body, studs secured to the slides and engaging opposite ends of said spring, and means for operating the levers to close the die.

2. In an opening die, the combination with a die-body having guides and reciprocating slides mounted therein, of levers pivoted to said die-body with one of their ends bearing against the slides, studs secured to said slides, a spring located between said studs, and a cam ring rotatably mounted on 25 30 the die-body and engaging the other ends of said levers.

In testimony whereof, I have hereunto set my hand.

H. H. WELSH, JR.
